UNITED STATES PATENT OFFICE.

JAMES M. CONNER, OF GREENVILLE, NEW JERSEY.

DESIGN FOR THE LOWER-CASE LETTERS OF A FONT OF PRINTING-TYPES.

Specification forming part of Design No. 8,892, dated January 11, 1876; application filed November 18, 1875.
[Term of Patent 7 years.]

CASE B.

To all whom it may concern:

Be it known that I, JAMES M. CONNER, of Greenville, Hudson county, New Jersey, have invented and produced a new and original Design for the Lower-Case Letters of a Font of Printing-Types, of which the following is a specification:

The nature of my design is clearly shown in the accompanying typographic impression, to which reference is made; and consists of a letter partly Roman and partly antique, made very open and round-cornered or arched at the ceriph or hair line.

What I claim as new is—

The design for the lower-case letters of a font of printing-types, as shown.

JAMES M. CONNER.
